APPARATUS FOR DETECTING HIGH-TENSION

ENDS IN A THREAD SHEET

Hal R. Newcome, Columbia, S.C., assignor to Allied Chemical Corporation, New York, N.Y., a corporation of New York

Filed Mar. 28, 1966, Ser. No. 537,950
5 Claims. (Cl. 28—35)

This invention relates to an apparatus for detecting high-tension ends in a horizontal sheet of a multitude of parallel yarn ends. More particularly, the invention relates to a device for detecting high-tension ends in a multitude of parallel yarn ends prior to put-up on a warp beam.

In the production of cloth, it has been a practice of long standing to take packages of drawn yarn or filaments and to load them onto a creel and thereafter to run the individual yarn ends from each creel onto large, flanged cylinders known throughout the textile industry as beams. A beam represents the largest yarn package available and as is known, is employed in connection with a loom which serves to weave the individual fibers to form a woven cloth.

The production of a woven cloth of acceptable quality requires that the individual yarn ends put-up on a beam be of even or substantially even tension. A representative prior art device for detecting threads which are under uneven tension includes a pivotable member which is connected to each of a plurality of yarns. When there is a breakage or slackening of any thread, the member contacts a conducting bar to complete an electric circuit with stop-motion mechanism which stops the feed of the thread or yarn. Generally, prior art devices of this type are not entirely satisfactory from a practical commercial standpoint because it is obvious that considerable time is required to pass each thread through the pivotable member, and moreover, it is difficult to locate the uneven tensioned yarn among the plurality of yarn ends when the pivoted member makes contact with the conducting bar to activate the stop-motion.

It is an object of the present invention to provide an apparatus for detecting high-tension ends in a threaded sheet. Another object is to provide an apparatus in the form of a single unit as opposed to the individual units for each yarn end previously employed, which apparatus continuously and automatically monitors all the yarn ends in the sheet.

A further object is to provide an apparatus which easily identifies to the observer the uneven tensioned thread.

Still another object is to provide an apparatus for monitoring tension of the yarn at a point just prior to take up onto the beam. Other objects and advantages will be apparent from the following detailed description.

In accordance with the present invention, there is provided an apparatus for detecting high tension ends in a horizontal sheet of parallel yarn ends which comprises two supports disposed one on each side of said parallel yarn ends, a traverse cradle guide disposed transversely over said yarn ends and supported by said supports, a traverse cradle including a frame transversely movably mounted on said traverse cradle guide having detecting means for detecting said high tension ends, and stopping means for stopping the transverse movement of said frame proximate to the site of said high tension end, and driving means associated with said cradle for driving said cradle at a uniform speed back and forth transversely across said parallel yarn ends including limiting means for limiting the extent of transverse travel of said cradle.

For a clearer understanding of the invention, reference is made to the drawings in which

FIGURE 1 is a front view in perspective showing the

2

apparatus disposed over a plurality of horizontal yarns and

FIGURE 2 is a view of the cradle showing activation when the cradle encounters a high tension yarn end.

Referring to FIGURE 1, it will be seen that the apparatus comprises two supports 10 and 11, disposed one on each side of a plurality of horizontal threads or yarns 12 which, for purposes of convenience, are hereinafter called yarn ends. Extending from the inner wall of support 11 is an arm 13 rigidly secured to the support 11 and which carries an idler pulley 14 which rotates about the axle 15 extending at substantially right angles from the arm 13. On the other side of the yarn ends 12 is a drive pulley 16 which is maintained in fixed relation with axle 17, the latter also carrying another pulley 9 enclosed in pulley housing 18 which is in driving engagement with pulley 19a and by means of pulley belt 8 in conjunction with motor 19 is adapted to cause rotation of the pulley 16 in clockwise or counterclockwise direction. Located below the arm 13 on support 11 is a traverse cradle guide 20, one end of which is rigidly secured to the inner wall of the support 11. The other end of the cradle guide is secured to support 10 on the front face thereof by any convenient manner such as by welding the extension 21 of the cradle guide to the support 10. As will be seen in the drawing, the cradle guide has a U-shaped cross section which provides a passageway or track extending across the entire length of the traverse cradle guide 20.

Mounted for movement across the traverse cradle guide 20 is a traverse cradle 21 which includes a frame 22 having a configuration as shown in FIGURE 1. It will be seen that toward the upper back portion of the frame are mounted a pair of rollers 23 which are positioned in the traverse cradle guide so that they rotate either clockwise or counterclockwise along the U-shaped portion of the guide and carry with them the frame 22. The upper front portion of the frame has two cross members 24 having downwardly projecting rods located one at each end of the cross members, and which pass through the base plate 25. The base plate forms the lower portion of the frame 22 and is supported by nuts 26 which threadably engage the lower ends of the rods 27.

Referring to FIGURES 1 and 2, centered approximately in the middle of the base plate near the forward edge thereof is a feeler finger 28 pivotably mounted with respect to the base plate by means of pivot pin 29 which passes through the feeler finger 28 and into the element 30 rigidly mounted on the base plate. The lower end of the feeler finger is positioned immediately over the plane of the horizontal parallel yarn ends 12 in an out-of-contact relation with the plane of the horizontal yarn ends.

Extending one from each side of the feeler finger are projections 31 which are substantially parallel with the base plate 25 when the feeler finger is vertically disposed. The terminals 32 on either end of the projections are positioned a relatively short distance away from cut-off switches 33 and one of said projections contacts the lug 34 of the cut-off switch 33 when the feeler finger pivots clockwise or counterclockwise as will be hereinafter explained.

As will be seen in FIGURE 1, a pulley cable 38 extends over the yarn ends 12 and around pulleys 14 and 16 with the ends of the pulley cable being affixed to the frame 22 of the cradle 21 at locations A and B. It will be obvious that rotation of pulley 16 clockwise or counterclockwise will exert a pulling force on the cradle by means of the cable pulley 38 and will cause the rollers 23 to roll along the U-shaped cross section of the traverse guide carrying with them the cradle which travels in the direction of the pulling force applied at locations A or B.

Located within the pulley housing 18 is the end of axle 17 mounted in bearings, not shown, and which carries an-

other pulley rigidly associated with the axle. Located immediately adjacent the support 10 is a motor 19 which supplies the driving force for the apparatus. The motor is of a conventional type and is of the class which is capable of instantly reversing the direction of rotation of the shaft 35 by an electrical receiving system, not shown. Located on the motor shaft 35 and rigidly secured thereto is a pulley 19a which accommodates a pulley belt 8 which extends around pulleys 19a and 9 in driving arrangement therewith. Positioned above the yarn cradle guide 20 are a pair of limit switches 36 positioned so that they extend one on each end slightly beyond the edges of the horizontal yarn ends 12. It will be observed that there are notches 37 at the lower end of these limit switches through which the pulley cable 38 is permitted to travel. Strategically located on the pulley cable 34 are limit buttons 38a which are positioned so that when one of the limit buttons 38a contacts the limit switch 36 most closely related thereto, the cradle 21 at this point has completely cleared the yarn ends 12 and the direction of travel of the cradle is reversed over the yarn ends. This direction of travel of the cradle is effected by means of circuitry and relays, not shown, in communication with the motor 19. The limit button 38a contacts the limit switch 36 most closely related thereto which causes a circuit to be energized and to send an impulse to the motor to reverse the direction of the shaft 19a.

Thus, the cradle 21 periodically alternately travels back and forth across the yarns until the apparatus is stopped or until the feeler finger encounters a high tensioned yarn as shown in FIGURE 2. When a high tensioned yarn is encountered, the finger 28 pivots and one of the terminal ends 32 contacts the lug 34 which energizes a circuit, not shown, to send an impulse to the motor which immediately cuts down the motor, stopping the travel of the cradle.

In a representative technique of operation, and assuming the cradle is in a position as shown in FIGURE 1 of the drawing, the motor is energized and causes rotation for example, clockwise, of the shaft 35, and pulley 19a. The pulley in pulley housing 18 is also rotated clockwise causing pulley 16 to rotate in clockwise direction. The cable pulley 38 then traverses a path towards the idler pulley 14 and carries with it the cradle 21 with the finger in substantially vertical position across the yarn ends. When a yarn end of high tension is encountered, that is, when a yarn end is above the plane of the horizontal yarn ends, the feeler finger pivots to the left causing the terminal 32 to contact lug 34 which energizes a circuit and causes the motor to come to a complete stop. The yarn cradle at this point, overlies the uneven tensioned yarn with the feeler finger either adjacent the uneven yarn end or in close proximity thereto thereby permitting the operator to locate the uneven yarn end in a simple and efficient manner. When the uneven yarn end is located and the tension corrected to correspond to substantially the same tension in the horizontal yarn ends, the apparatus is again started and the cradle thereafter continues its travel across the yarn ends until limit button 38a energizes limit switch 36. At this point, the feeler finger has cleared the horizontal yarn ends located immediately below. Contact of limit button 38a with the limit switch 36 through relays and circuitry, not shown, sends an impulse to the motor causing the shaft 35 to reverse rotation. By means of the drive arrangement previously explained, the traverse pulley cable then rotates in opposite direction and the traverse cradle proceeds back across the horizontal yarn ends until either another uneven tensioned yarn is located or until limit button 38a contacts limit switch 36 to reverse the path of travel of the cradle.

While a preferred embodiment of the apparatus of this invention has been described, it is apparent that many changes of material and modifications of design can be made without departing from the concept of the invention.

The nature of the filamentary structure being monitored is not critical. Threads or continuous-filament yarns composed of either man-made or natural fibers can be

monitored according to the present invention. Several advantages are derived from the practice of this invention, primary among which are, low operating cost as well as the ease and simplicity in which the high tension yarn end is located. The apparatus may be easily mounted immediately before a warp beam thereby providing a warp beam having ends under substantially even tension. Other advantages inherent in the practice of this invention will occur to those undertaking its practice.

10 I claim:

1. Apparatus for detecting high tension ends in a horizontal sheet of parallel yarn ends which comprises two supports disposed one on each side of said parallel yarn ends, a traverse cradle guide disposed transversely over 15 said yarn ends supported by said supports, a traverse cradle including a frame transversely movably mounted on said traverse cradle guide having detecting means for detecting said high tension ends and stopping means for stopping the transverse movement of said frame proximate to the 20 site of said high tension end, and driving means associated with said cradle for driving said cradle at a uniform speed back and forth transversely across said parallel yarn ends including limiting means for limiting the extent of transverse travel of said cradle.

2. Apparatus according to claim 1 wherein said traverse cradle guide has a U-shaped cross section and wherein said detecting means includes a base plate attached to the lower end of said frame, a feeler finger pivotably vertically mounted on said base plate said finger having a pair of 30 projections extending one from each side of said feeler finger the lower end of said feeler finger being positioned immediately over the plane of said horizontal parallel yarn ends, and wherein the stopping means include a pair of cut-off switches mounted on said base plate one on 35 each side of said finger, said cut-off switches having lugs extending therefrom, said stopping means being adapted to stop the transverse travel of said cradle when said feeler finger encounters a high tension yarn whereby said finger pivots sufficiently to effect contact of one of said lugs with 40 one of said projections on said finger.

3. Apparatus according to claim 2 wherein said frame carries a pair of rollers at the upper portion thereof, said rollers being in rolling engagement with said U-shaped cross section of said traverse cradle guide to permit said cradle to travel a path transversely with respect to said 45 yarn ends.

4. Apparatus according to claim 3 wherein said driving means includes a drive motor having a shaft with a pulley mounted thereon, an axle rotatably mounted on said support and carrying an inner pulley and an outer pulley, 50 said inner pulley being associated with said pulley on said motor shaft, said outer pulley being a driving pulley adjacent one support and disposed on one side of said yarn ends, an idler pulley mounted on said other support being positioned on the other side of said yarn ends, a traverse 55 cable pulley in contact with said driving pulley and idler pulley and being attached to said cradle whereby said cradle travels a path transversely across said yarns when said driving and idler pulleys are rotated.

5. Apparatus according to claim 4 wherein said limiting 60 means includes limit switches disposed one on each support and limit buttons positioned on said cable pulley whereby one of said buttons contacts one of said limit switches to limit the extent of transverse travel of said cradle and to cause said cradle to traverse a path in opposite direction to previous path of travel.
